TITANIUM BASE ALLOYS

Harold Margolin, Mount Vernon, and William Frank Kirk, Bronx, N. Y., assignors to Kennecott Copper Corporation, New York, N. Y., a corporation of New York

No Drawing. Application October 16, 1956
Serial No. 616,120

7 Claims. (Cl. 75—175.5)

This invention relates to titanium base alloys, and provides improved titanium base alloys comprising lead, aluminum, vanadium and tin with or without zirconium, as the essential alloying metals. The alloys of this invention comprise up to about 4% lead, up to about 7% aluminum, up to about 2.5% vanadium, up to about 20 2.5% tin, and when zirconium is included it is used in

2

good ductility and other desirable properties including good machinability, high modulus of elasticity, good cold workability and good elevated temperature properties.

The improved titanium base alloys of the invention accordingly comprise titanium as the major constituent, and from 0.1% to 4% of lead, from 3% to 7% of aluminum, from 0.5% to 2.8% of vanadium, from 0.5% to 2.5% of tin, and up to 4%, preferably from 0.5% to 3.5% of zirconium, when this metal is used. Oxygen 10 and nitrogen are considered to be objectionable impurities in these alloys and, if present should, in the aggregate, be in an amount less than about 0.2%. It is to be understood that the alloys may include the usual impurities contained in the ordinary commercial metals used in forming the alloys, and small amounts of one or more other metals which do not alter in any practical sense the characteristics of the alloys.

Typical titanium base alloys of this invention are illustrated in the following Table I which shows their compositions and mechanical properties. The titanium is the unrecorded balance.

Table I

Alloy No.	Analyzed Composition					Specific Gravity	Tensile Strength (p. s. i.)	0.2% Off. Y. S. (p. s. i.)	Percent Elong. (1")	Percent Red. in Area	Modulus of Elasticity (p. s. i. $\times 10^{-6}$)	VHN (10 kg.)	Treatment*
	Percent Pb	Percent Al	Percent V	Percent Sn	Percent Zr

We claim:

1. Titanium base alloys consisting essentially of from 0.1% to 4% of lead, from 3% to 7% of aluminum, from 0.5% to 2.8% of vanadium, from 0.5% to 2.5% of tin and the balance of alloying metal being titanium, 20 said alloys having tensile strengths in excess of 136,000 p. s. i. coupled with good ductility, as represented by a reduction in area of at least 8.7%.

2. Titanium base alloys consisting essentially of from 0.1% to 2.5% of lead, from 3% to 7% of aluminum, 25 from 0.5% to 2.8% of vanadium, from 0.5% to 2.5% of tin.

3. Titanium base alloys consisting essentially of from 0.1% to 1.5% of lead, from 3% to 7% of aluminum, from 0.5% to 2.8% of vanadium, from 0.5% to 2.5% of 30 tin.

4. A titanium base alloy according to claim 1 consisting essentially of from 0.5% to 3.5% of zirconium.

5. A titanium base alloy according to claim 2 con-

sisting essentially of from 0.5% to 3.5% of zirconium.

6. A titanium base alloy according to claim 3 consisting essentially of from 0.5% to 3.5% of zirconium.

7. A titanium base alloy according to claim 1 which consists of up to 4% zirconium.
